UNITED STATES PATENT OFFICE.

GEORGE G. POWELL, OF NEW YORK, N. Y., ASSIGNOR OF ONE-HALF TO IGNATIUS V. McGLONE, OF JAMAICA, NEW YORK.

METHOD OF MAKING CONCRETE PILES.

Application filed June 7, 1921. Serial No. 475,774.

To all whom it may concern:

Be it known that I, GEORGE G. POWELL, citizen of the United States, and resident of the borough of Bronx, New York city, in ⁵ the county of Bronx and State of New York, have invented certain new and useful Improvements in a Method of Making Concrete Piles, of which the following is a specification.

¹⁰ This invention relates to improvements in the method of making concrete piles, caissons and the like with enlarged footings or enlargements at other portions thereof.

The object of the invention comprises improvements in such a method whereby such enlarged footings or other enlargements for piles of concrete and similar material can easily and cheaply be made when the piles are located in soft or yielding soil and also ²⁰ when the footings are to bear on the surface of rock or other hard substances.

The piles produced by this improved method obviate the necessity of using long and spliced piles in soft ground to obtain ²⁵ the requisite skin friction for their support.

This improved method obviates the necessity of using the air lock method and the expensive equipment for compressed air and air locks and allows the use of short piles ³⁰ with great frictional resistance to maintain loads thereon without displacement.

The organization of the invention comprises driving a casing into the soil, and removing the soil from the interior thereof, ³⁵ by the use of a water jet or other method. Then a tube with electric conductors is located in the casing. A container with an explosive is attached to the lower end of the tube and tube with the container is forced ⁴⁰ below the bottom end of the casing. The casing is then filled with liquid concrete and thereafter the explosive is exploded which forms a cavity in the soil below the casing. After the explosion the gases in the cavity ⁴⁵ condense whereby the concrete in the casing lowers and fills the said cavity to form a footing.

In the drawings Fig. 1 represents a sectional elevation of a casing driven into its ⁵⁰ surrounding soil; Fig. 2 shows a casing similar to Fig. 1 with a conduit and its appurtenances;

Fig. 3 shows a view similar to Fig. 2 with the casing thereof filled with concrete;

Fig. 4 indicates a sectional elevation similar to Fig. 3 with a footing at its lower end; Fig. 5 shows a view similar to Fig. 4 with the casing filled with concrete; Fig. 6 shows a sectional elevation similar to Fig. ⁵⁵ 5 with a modification;

Fig. 7 shows another sectional modified elevation of a casing with its appurtenances;

Fig. 8 represents a sectional elevation of a casing driven into its surrounding soil with a plurality of conduits and their appurtenances; Fig. 9 shows a view similar to Fig. 8 with a modification; Fig. 10 is a top view of Fig. 9; Fig. 11 indicates a sectional elevation of a plurality of concrete piles connected together; Fig. 12 shows a section ⁶⁰ of Fig. 11 on the line 12, 12; Fig. 13 shows an elevation of a bridge made of concrete piles, and Fig. 14 is a section of Fig. 13 on the line 14, 14.

Referring to the accompanying drawings ⁶⁵ Figs. 1 to 6 indicate the steps of an exemplification of the invention. In Fig. 1 a casing 20 is indicated which is driven into the soil 21. The soil in the interior of the casing is then removed by a water jet or other suitable method. Next as indicated in Fig. 2 a conduit 24 with electric conductors 25 therein and a container 26 with an explosive is lowered in the casing. The container 26 is forced below the lower end ⁷⁰ of the casing in the soil 21. Then, as indicated in Fig. 3 the casing 20 is filled with liquid concrete 30. The next step consists in exploding the explosive in the container 26 by means of a source of electric current ⁷⁵ 90 for the conductor 25, to form cavity 33 below the bottom end of the casing 20 as shown in Fig. 4. Upon the condensation of the gases in the cavity 33 the liquid concrete 30 will flow into the said cavity 33, ⁸⁰ 95 and form the enlarged footing 34, the upper level of the concrete in the casing 20 at the same time descending. The next step is to fill the casing 20 with concrete to its upper end as indicated in Fig. 5, which concrete ⁸⁵ 100 is next allowed to harden. If it is desirable to remove the casing 20 from the concrete pile it must be done before the concrete hardens. The concrete pile with its enlarged footing 34 is now complete.

In Fig. 6 a casing 40 is indicated which tapers outwardly from its top to its bottom end and which has formed therein the concrete

pile 41 with the enlarged footing 42. The latter is supported on the bed of rock 44. The latter has been cleaned at its upper face and has a cavity 45 formed therein as a result of the explosion of the explosive charge and which forms a good seat for the enlarged footing 42. In Fig. 7 is indicated a casing 50 which tapers inwardly from its top to its bottom end and which contains the concrete pile 51 with the enlarged footing 52.

In Fig. 8 is indicated a casing 60 in the soil 21, with a plurality of conduits 61, 62 and 63 with their electric conductors 64 and 15 their respective containers 66, 67 and 68 with explosives. In this modification as previously described liquid concrete is poured into casing 60 and then explosives in the containers 66, 67 and 68 are exploded. 20 This will produce a cavity 69 at the bottom of the casing and bulge out said casings at the sides as indicated at 70. The liquid concrete will then flow into said cavities and form an enlarged footing at the bottom of 25 the pile and an enlargement at the sides thereof. The containers with explosives in the casing may also be located at various other levels to form a plurality of enlargements at the sides of the pile at different 30 levels. If the casing 60 in this exemplification is to be removed it must be done after the footing is formed at the bottom of the pile and before the explosives in the containers 66 and 67 form the bulged-out portions 35 at the sides of said pile.

In Figs. 9 and 10 a large casing or caisson is indicated at 75 which is driven into the soil 20 to near bed rock and a plurality of conduits 76 with electric conductors 77 and 40 containers 78 are lowered in said caisson 75 after the soil therein has been removed. When the explosives in the containers are exploded a large continuous footing is 45 formed in the cavity 79. In this instance the cavity 79 is partly formed in the bed rock 80 to make a clean and perfect contact for the footing.

In Figs. 11 and 12 an adaptation of the concrete piles is exemplified and in which 50 Fig. 11 indicates a side elevation of a plurality of piles 82 with enlarged footings 83 that make one continuous footing for the piles. These piles are formed in the way already explained. A cap 84 is supported 55 on the piles 82. Fig. 12 shows a cross-section of Fig. 11 on the line 12, 12.

In Figs. 13 and 14 another adaptation of the piles is indicated and in which Fig. 13 shows a sectional view of a stream with the 60 piles and Fig. 14 shows a section of Fig. 13 on the line 14, 14. The rock forming the channel for the river is shown at 90 and which has supported thereon the soft soil 91. A plurality of concrete piles 92 are 65 formed with the steps already described

which with their enlarged footings 93 form an arch in the soil 91. A cap or roof 95 is located on the top ends of the concrete piles 92.

Having described my invention what I desire to secure by Letters Patent and claim is:

1. The method of forming a concrete pile consisting in forcing a casing into the soil, removing the soil from the interior of the casing, locating an explosive in the soil below the bottom end of the casing, filling the casing with liquid concrete and exploding said explosive in said soil, said concrete flowing into the cavity formed by the explosive and forming an enlarged footing for the pile.

2. The method of forming a concrete pile consisting in forcing a casing into the soil, removing the soil from the interior of the casing, locating an explosive in the soil below the bottom end of the casing, filling the casing with liquid concrete, exploding the explosive and thereby forming a cavity directly in the soil below the concrete in the casing, the concrete thereof flowing into said cavity to form an enlarged footing for the pile, the concrete lowering in the casing and then filling the casing with additional concrete.

3. The method of forming a concrete pile with an enlarged footing and bulged out portions at the sides thereof, consisting in forcing a casing into soil, removing the soil from the interior of the casing, locating a plurality of conduits each with electric conductors and a container at the lower end in the casing, some of said containers suspended between the top and bottom ends of the casing and some in the soil below the bottom end of the casing, filling the casing with liquid concrete, exploding the explosives in the containers to form a cavity below the casing and bulge the latter at the sides thereof, the said concrete after the explosion flowing into said cavity to form a footing and flowing in the bulged portions of the casing to form enlargements at the side of the pile, the liquid concrete lowering in the casing as a result of the explosion and then filling the casing with additional liquid concrete.

4. The method of forming a large concrete pile by forcing a caisson into soil, removing the soil from the interior of the caisson, lowering a plurality of conduits each with electric conductors and a container with an explosive at its lower end into the caisson forcing the conduits with the containers in the soil below the bottom end of the caisson, filling the caisson with liquid concrete and exploding the explosives in the containers to form a plurality of cavities at the lower end of the caisson, the liquid concrete flowing into the cavities forming an

enlarged footing for the pile and then filling the caisson with concrete up to its upper level.

5. The method of forming a plurality of concrete piles with their footings forming a supporting wall consisting in forcing a plurality of casings adjacent to each other in the soil, removing the soil from the interior of each casing, lowering a conduit with 10 electric conductors and a container at the bottom end of each conduit in each casing, forcing the lower end of each conduit with the container in the soil below the bottom

end of each casing, filling each casing with liquid concrete and exploding the explosive 15 in the containers forming a plurality of cavities, the concrete flowing into the cavities to form a supporting wall by reason of the footings formed becoming connected to each other.

20 Signed at the borough of Manhattan, city of New York in the county of New York and State of New York this 3d day of June, A. D. 1921.

GEORGE G. POWELL.
